UNITED STATES PATENT OFFICE.

CHARLES H. WILLSON, OF MEDFORD, ASSIGNOR TO JAMES W. BROOKS, OF PETERSHAM, AND FRANK F. STANLEY, OF SWAMPSCOTT, MASSACHUSETTS, TRUSTEES.

DESIGN FOR A NAIL OR SLUG.

SPECIFICATION forming part of Design No. 25,081, dated January 21, 1896.

Application filed December 18, 1895. Serial No. 572,604. Term of patent 3½ years.

To all whom it may concern:

Be it known that I, CHARLES H. WILLSON, of Medford, county of Middlesex, and State of Massachusetts, have invented and produced 5 a certain new and useful Design for a Nail or Slug, of which the following is a specification, reference being had to the accompanying drawings, forming a part thereof.

Figure 1 of the drawings is an isometric view of a nail or slug, illustrating my design; and Fig. 2 is an end view thereof.

The leading feature of my design for a nail or slug consists in a flat web flared along one longitudinal edge to join a larger portion substantially semicircular in cross-section and intersecting at its other longitudinal edge an enlarged portion substantially square in cross-section.

In the drawings the flat web a is flared at a^1 along one longitudinal edge to join a larger portion a' , substantially semicircular in cross-section, a part a^2 substantially square in cross-section being connected along one of its corners to the other longitudinal edge of the web a . 25

I claim—

The design for a nail or slug, substantially as set forth.

In testimony whereof I have signed my name to this specification in the presence of 30 two subscribing witnesses.

CHARLES H. WILLSON.
